LOUIS STEINBERGER, OF BROOKLYN, NEW YORK.

DISK STRAIN-INSULATOR.

1,223,909.

Specification of Letters Patent. Patented Apr. 24, 1917.

Application filed January 3, 1913. Serial No. 739,988.

To all whom it may concern:

Be it known that I, LOUIS STEINBERGER, residing at Brooklyn, in the county of Kings and State of New York, have invented certain new and useful Improvements in Disk Strain-Insulators, of which the following is a specification.

This invention relates to strain insulators, and particularly to those of the disk type.

10 A particular object of the invention is to provide an insulator of this class wherein the irregularities of surface, for providing water sheds and otherwise increasing the insulating value of the disk without increasing the size of the disk, are arranged in such manner that they are amply supported from the body without depending for their support upon the strength of intervening relatively weak portions of the structure.

20 A further object is to provide a structure as above, which comprises ridges formed on the surface of the disk radiating from the body, and to shape, or curve, the ridges after leaving the body, so as to dispose a plurality of distinct ridges in the path of any current tending to creep radially across the surface of the disk.

A further object is to provide a disk with ridges on its opposite surfaces radiating 30 from the body of the insulator, and to shape, or curve, the ridges upon the opposite surfaces of the disk in such directions that portions of the ridges upon the respective surfaces will lie in intersecting planes for lending added strength to the structure.

A further object is to provide a structure, as above, which is simple of design, which comprises a minimum of material and which is therefore cheap to manufacture, but is nevertheless thoroughly substantial and embodies maximum efficiency, both as to its insulating qualities and as to its mechanical strength, for a given sized disk.

45 A further object is to provide an insulator comprising spaced conductors, to provide means intermediate the conductors defining creepage paths, and to so shape the paths as to obtain maximum efficiency for a given size insulator.

50 Other objects and aims of the invention, more or less specific than those referred to

above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown a merely preferred form of embodiment of the invention:

Figure 1 is a top plan view of an insulator constructed in accordance with the principles of this invention;

Fig. 2 is a side elevational view of the structure shown in Fig. 1; parts being shown in section and the plane of line 2—2 of said figure;

Fig. 3 is a fragmentary, detail, sectional view, taken substantially on the plane of line 3—3 of Fig. 1.

Referring to the drawings for a more detailed description of the structure illustrated, the numeral 1 indicates the body portion of the insulator, which portion is preferably of a more or less elongated cylindrical shape, adapted for receiving the strain members illustrated at 2 and 3.

The strain members illustrated each comprise a short bolt having an eye, as 4, at its outer end, and having its inner end formed with a head 5, shown in dotted lines in Fig. 2. The inner ends of the two strain members are spaced apart and the material of the body fills the intervening space for effectually insulating the members from each other.

It will be understood that, though I have shown and described the strain members as comprising simple bolts having heads spaced apart and molded within the body 1 in axial alinement, said strain members may, of course, take any other form desired for increasing the mechanical strength of the structure in resisting strains placed upon the strain members, or for increasing the insulating value of the structure.

The disk portion of the structure is illustrated generally by the reference numeral 6, and comprises a wall or annular flange of

substantially uniform thickness springing from the body 1 between the ends of the body, preferably at the transverse median line of the body.

5 Formed upon the upper surface of the wall or flange forming the disk portion 6 is a plurality of ridges 7, each of the ridges extending from the body portion 1 preferably to or near the outer peripheral edge of 10 the disk. These ridges preferably leave the body substantially radially thereof and extend in a curved convolute or spiral direction along the surface of the disk toward the periphery thereof.

15 The ridges may be considered as merging together in a common point at the body, and there is preferably enough of them, and their shape is such, that the outer portions of any one of them radially overlap at least 20 one or more of the adjacent ridges, so that a line drawn radially from the center of the disk will intersect at least two ridges. This arrangement is not a positive requirement for effective operation of the structure, but 25 is a preferable one. As many or as few ridges may be employed as deemed desirable for meeting various requirements, both as to withstanding different degrees of potential 30 and of attaining required mechanical strength.

The thickness of the material forming the wall or flange 6 may preferably be only sufficient to lend efficiency against puncturing and for lending the required mechanical 35 strength to reinforce the outer portions of the ridges.

The ridges 7 are preferably of a relatively greater cross sectional area where they merge together, or into the body of the insulator, and gradually decrease in proportions 40 toward the periphery of the disk, as clearly shown in the drawing. This will lend strength to the structure, both electrically and mechanically.

45 In order to further strengthen the structure, and to more effectually guard against puncture, it may be desirable to increase the thickness of the wall or flange 6 in the vicinity of the body 1. The flange may be 50 made thickest adjacent the body and be of gradually decreasing thickness toward the edge, or it may be otherwise reinforced, as desired. Here it may be noted that wherever in this specification or claims, the term 55 "substantially of uniform thickness" or its equivalent is employed to describe the portion 6, such term is intended to include any variations in thickness which may be desirable for lending required strength and resistance to puncturing to the part.

60 It is apparent that the structure shown and described, provides ridges and depressions radially of the disk, with all the advantages thereof, but without the necessity 65 for proportioning the intervening parts of

the disk between the ridges beyond the requirements for preventing puncture. The integral connection of the ridges with the body greatly increases the mechanical strength of the structure.

70 It should be noted that though I have shown and described the ridges 7 as being distinctly prominent and spaced apart by substantially flat portions of the flange or wall 6, it is however obvious that these 75 ridges could as well be rounded on their surfaces, one ridge merging gradually into the next adjacent ridge, or they may be given any other desired cross sectional contour, within the spirit of this invention.

75 It is apparent that the depressions or grooves formed between the ridges 7 serve to present relatively dry areas even in the presence of rain fall. At least one side of 80 the structure will necessarily be almost entirely dry. These depressions or grooves also define creepage paths radiating from the center of the disk and, by reason of the convolute or spiral direction of the ridges, the creepage paths are considerably longer 85 than the radial dimension of the disk. The proportions of the ridges may be calculated so as to cause the space between them to 90 serve as creepage paths throughout the length of the ridges.

95 Supposing the insulator to be arranged with its axis substantially horizontal, as illustrated in Fig. 1, water, as rain, striking the surface will be conducted around the body 1, and will fall off the lowest point of 100 the insulator. In the drawings there are shown two lines, X and Y, for indicating the probable path of a great proportion of such water as would strike the top of the insulator at the points of the lines X and Y.

105 It will be noticed that these lines follow paths of easiest flow indicated by the shape of the ridges, and that water following these paths will be conducted away from the body 1, and consequently away from the strain 110 members within the body. Such water as may strike the top of the insulator intermediate the lines X and Y, will probably follow an intermediate path as indicated by the line Z, which path may conduct the water 115 nearer to the body than either of the paths X and Y. The amount of water following the path Z, however, is so small as to be practically negligible, and will reach the body at one side of the center thereof, and 120 will be conducted around that side of the body and prevented from moving toward the strain member at the end of the body.

125 Due to the influence of surface cohesion, some of the water may follow directly along the ridges and into the pockets 8 formed adjacent the body between the ridges, rather than follow the steeper and easier paths indicated by the lines X and Y, but since the 130 body projects beyond the outer edge of the

ridges, this water will pass around the sides of the body toward the bottom rather than to the end of the body.

The opposite surface of the wall or flange 5 6 is provided with ridges in every way similar to those already described, and these ridges may be arranged directly beneath the ridges described, if desired. They are however preferably curved in a relatively opposite direction, as shown best by dotted lines 10 9 in Fig. 1, so that the ridges upon the two surfaces of the disk cross or intersect each other to lend added strength to the structure. The creepage paths are also lengthened by this arrangement. In the arrangement 15 shown each of these paths follows a line extending from one side of one conductor, making a wide circle across one surface of the disk to the periphery thereof, and continues across the other surface of the disk to a relatively opposite side of the other conductor. Maximum efficiency against creepage 20 is thus secured for a given sized disk.

When desired, an annular groove 10 may 25 be formed upon the periphery of the disk by the addition of obliquely projecting flanges 11 which will serve to effectually protect the surfaces of the disk from direct attack of rain water. Such water as strikes the 30 flanges 11 will be conducted to the lowest point and fall off without reaching either surface of the disk.

As many changes could be made in this construction without departing from the 35 scope of the following claims, it is intended that all matter contained in the above description or shown in the accompanying drawing shall be interpreted as illustrative only and not in a limiting sense.

40 Having thus described my invention what I claim as new and desire to secure by Letters Patent, is:

1. In an insulator, a disk formed with a 45 plurality of ridges thereon radiating from a common point and extending in curved directions so that one ridge overlaps a portion of another ridge radially from said common point.

2. In an insulator, a disk formed with a 50 central body portion, and a series of ridges formed on said disk extending from said body portion in curved directions toward the margin of the disk, and a portion of one 55 of said ridges overlapping a portion of another of said ridges radially from said body portion.

3. In an insulator, a disk, and means thereon defining a plurality of creepage paths extending in curved directions from the central portion of the disk toward the periphery thereof, said paths having portions overlapping radially from said central portion of the disk.

4. In an insulator, a disk having relatively 60 upper and lower surfaces, a plurality of

spaced and separate ridges extending along said two surfaces in a spiral direction, and the ridges on one surface extending in a spiral direction opposite to the direction of the ridges on the other surface.

5. In an insulator, a disk having a plurality of ridges upon each of its opposite surfaces defining creepage paths between them, there being a creepage path upon one surface to form a pair with each creepage 70 path upon the opposite surface, the two creepage paths of each of said pairs extending from the central portion of the disk in substantially diametrically opposite directions but being curved so as to terminate adjacent a common point in the vicinity of the periphery of the disk.

6. In an insulator, a disk having a plurality of curved ridges on each of its opposite surfaces, the ridges on each surface radiating from a common point, and the ridges on one surface curving in a direction opposite to the direction of curve of the ridges on the other surface, and portions of the ridges on one surface overlying portions of 85 the ridges on the other surface.

7. A disk insulator having a creepage path upon each of its opposite surfaces, the creepage path upon one surface forming a pair with the creepage path upon the opposite 90 surface, the two creepage paths extending from the central portion of the disk in substantially diametrical opposite directions, but being curved so as to terminate adjacent a common point in the vicinity of the 95 periphery of the disk.

8. In an insulator, a disk having a plurality of ridges on each of its opposite surfaces, the ridges on each surface radiating from a common central point and extending 100 in curved directions toward the margin of the disk, the ridges upon the respective surfaces of the disk being disposed so that relatively outer portions of each overlap relatively inner portions of adjacent ribs radially of the disk.

9. In an insulator, a disk having a plurality of ridges on each of its opposite surfaces, the ridges on each surface radiating from a common central point and extending 115 in curved directions to the margin of the disk, the ridges upon the respective surfaces of the disk being disposed so that relatively outer portions of each overlap relatively inner portions of adjacent ribs radially of the disk, said ridges upon the respective surfaces of the disks defining creepage paths between them extending outwardly from the central part of the disk to the margin of the disk, also said ridges being disposed so that each creepage path upon one surface forms a pair with a creepage path upon the opposite surface, each pair constituting a continuous creepage path extending from the 120 central portion of the disk outwardly in a 130

4
curved direction along one surface of the disk and inwardly along the opposite surface to the central portion of the disk, approaching the central portion in a direction substantially diametrically opposite to the direction in which it left said central portion.

In testimony whereof, I affix my signature in the presence of two witnesses.
